ATTORNEY

UNITED STATES PATENT OFFICE

FRANCIS E. WEIDHAAS, OF BRONXVILLE, NEW YORK

STAGE CURTAIN OR DROP

Application filed July 14, 1928. Serial No. 292,826.

My present invention relates to an improvement in method of, and apparatus for, stage fittings or scenic effects, and is more especially directed to an improvement in settings, wherein means are provided, as will 5 hereinafter be disclosed in detail, to vary the setting or background of a stage by the use of a curtain or curtains.

One advantage of my device is the provision, with a curtain or back drop, of means 10 whereby the curtain may be quickly and easily draped, as a setting, in the similitude of various objects, such as trees, tents, door openings, Gothic arches or conventionalized 15 ornamental representations or outlines thereof, either in solid outline or shadow form.

Various other forms of outline may be developed for the purpose above specified, such variations, of which a few are herein 20 disclosed, being unlimited, and my device being extremely flexible in this respect, such variations being only limited by the imagination of the scenic artists or the requirements of the act.

25 While I have only shown one curtain setting herein by way of illustration, a further obvious use is in the mounting of a plurality of curtains one behind the other, each of which is contourably draped to one portion 30 of the setting, the combined plurality of draped curtains creating any desired single ensemble.

Modifications may be made in the structural means herein disclosed, for the desired 35 accomplishment, without departing from the spirit of the invention or the scope of the appended claims.

In the accompanying drawings:

40 Fig. 1 represents the front view of the curtain drop, in broken view, showing its undraped proportions to the proscenium which is shown in dotted lines.

Fig. 2 is a rear view thereof showing the 45 structural details of the contour control means.

Fig. 3 shows a modification, rear view, of a different arrangement of the contour control means.

50 Fig. 4 shows a rear view of the curtain

contour control means arranged to delineate a conventional opening.

Figs. 5 to 13 show, diagrammatically, a series of unlike contours into which the curtain may be draped.

Fig. 14 is a plan view of one form of arrangement whereby the curtain contouring control cables are concentrated from their various points of connection with the curtain to a single station for easy and rapid manual 60 manipulation.

My device consists of a fabric curtain A, Figs. 1 and 2, which may be of any texture and color, or combinations thereof, and which is suspended upon any suitable means when 65 in undraped or draped position, such as a cable or bar 2; if a cable is used, two eyebars 3-3, suitably affixed to opposite walls or supports 4-4 keep the cable taut, and the curtain fixedly supported in full open suspension, as in Fig. 1. At this point of attachment the curtain may hang flat on the cable 2 without any fulling. In Fig. 1 the curtain is shown broken away at opposite ends, as at 70 A-A, for convenience in showing.

It will further be noted that, in Figs. 1 and 2, the curtain is much wider in dimension, over all, than the proscenium B, shown in dotted lines in both figures. This is for the purpose of providing an excess of curtain length, so that, when draped in desired contours, as in Fig. 4, the outer ends 5 of the curtain may not be exposed and destroy the desired effects, unless, as in some instances, the exposed ends provide a part of the desired contour design effect. However, the curtain in its over-all dimensions must be sufficiently ample over the width of the proscenium to permit of maximum take-up of its lower edge 6 in forming any desired contour, without 80 unduly straining or distorting the curtain into ungraceful folds or destroying the continuity of desired outline.

To create the various types of contoured forms of the curtain, as shown in Figs. 4 to 13, or any other form or shape, and to maintain it in desired set outline, any one of which is entirely formed by varying the suspension of the lower edge 6 of the curtain, it is necessary to provide such edge 6 with a 100

flexible weight member 7, shown as a heavy metal chain, the hem of the edge 6, in Figs. 1 and 2, being broken away in these two views in order to show the lay of the chain therein.

5 Any other form of articulate or flexible weight may be used. I have found that a chain, as described, is entirely satisfactory for the purpose.

With the chain 7 thus disposed in the lower hemmed edge 6 of the curtain, I then provide the curtain with a contouring control means consisting of a plurality of manually manipulatable lines or cables 8, Figs. 2 to 4 inclusive, these cables being affixed at their lower ends 9 to the chain filled hem edge 6. These lines are then run up to the top of the curtain, there to pass over a series of pulleys 10, one for each line 8, said pulleys being suitably mounted upon a support 11, which is in fixed relation to the curtain suspension means 2-3.

The opposite ends of the lines or cables 8 are led over the pulleys 10, to one side of the stage at which point there is affixed a plurality of drum pulleys 12, Fig. 14, these being 25 rotatably supported upon one side wall 4. The cables then pass over their respective pulleys, downwardly, with sufficient length to be manipulated, and after being set, to be attached to wall cleats 13, Figs. 2 to 4, and 14, 30 to hold the curtain in desired contour arrangement, one of which is shown at Fig. 4, with the edge 6 set in a conventional draped contour, which is firmly held in easy curves, by reason of the setting of the spaced cables 35 8 in drawn position, locked on the cleats and, also, by reason of the weight of the comparatively heavy chain in the hem edge 6 of the curtain.

In practice, it is understood that the control lines 8 are at the back of the curtain, away from public view.

A modified form of contour controlling cable attachment is shown in Fig. 3, wherein the lines 8 are crossed at the center of the curtain, running from any pulley 10, to a point of attachment on the opposite side of the curtain. This modified form permits of variation of curtain contours.

In the use of my device, such arrangements 50 of curtain contour, as are indicated in Figs. 4 to 12, provide for arrangements of contour wherein the curtain is drawn to expose different designs of openings D, whereas in Fig. 13 the ensemble there effected is substantially the reverse; in this latter view the curtain is so arranged by the manipulation of the proper hand lines 8, as to be itself the design or contour, delineating therein a conventionalized tree design.

What I desire to protect and claim is:

1. In combination with a suspended curtain and a pulley system, selective means to hold said curtain in a predetermined contour position, and a flexible means in said curtain to

positively retain the curtain in said contour position.

2. In a device of the class described, a curtain, flexible weight means associated with the curtain, a pulley system, and control means associated with said flexible means and said pulley system to position said curtain in a predetermined contour position. 70

3. In a device of the class described, a suspended curtain, flexible weight means associated with said curtain to retain it in suspended position, a pulley system, a plurality of selective and independently manipulatable means associated with said flexible means and said pulley system. 75

4. In a device of the class described, a curtain adapted to be suspended, means associated with a portion of said curtain to retain it in suspended position, a pulley system, a plurality of independent cables associated with said pulley system and said means, each of said cables being adapted for motion independently of the others. 80

5. In a device of the class described, a curtain adapted to be vertically suspended, flexible means associated with the lowermost portion of said curtain to maintain the same in suspended position, a pulley system, a series of independently manipulatable cables associated with said pulley system, said cables being associated with said flexible means in a progressive series. 85

6. In a device of the class described, a curtain adapted to be vertically suspended, a flexible weight means disposed along the lowermost edge of said curtain, a pulley system, a series of independently manipulatable cables associated with said pulley system, said cables being associated with said flexible means in a progressive series. 90

7. In a device of the class described, a curtain adapted to be vertically suspended, an articulated weight means disposed along the lowermost edge of said curtain, a pulley system, a series of cables associated with said pulley system and adapted to be independently manipulatable, the ends of said cables remote from said pulley system being associated with said weight means in sequence. 105

8. In combination with a suspended curtain and a pulley system a selective, manually operated means for changing the contour of said curtain into a desired outline and fixed means for holding said contour at will. 110

9. In combination with a suspended curtain, a plurality of fixed members and a pulley system, a curtain contour control means including a plurality of manipulatable means operatively associated with said curtain and said members and selectively applicable for varying the contour of the curtain at will. 120

10. In combination with a curtain and a plurality of fixed members a contour control means for the curtain, including a series of selective manipulatable means operatively 130

associated with said curtain, said members being positioned on the side of the curtain and said means being applicable for manually varying the contour of the curtain at will.

5 11. In combination with a curtain, a plurality of fixed members and a pulley system a contour control means for said curtain, including a plurality of independently selective and manipulatable means operatively associated with said curtain and disposed for manually varying any part of the contour of said curtain at will.

10 12. The method of forming a contour design with a curtain, which consists in loading the lower edge of the curtain with a flexible weight member, then raising suitable parts of said curtain at a number of points to the most pronounced positions of the required contour and then manipulating and adjusting the raising of the parts of the curtain at intermediate points on said curtain until the combined influence of the force of said weight member and said raising of said last mentioned parts produces the required contour.

15 13. In combination with a curtain and a pulley system a contour control means for said curtain, including a plurality of fixed parts, vertically disposed flexible members for suspending said curtain therefrom, said members extending each at one end thereof to the lower edge of the curtain and being connected at the other end thereof to one of said fixed parts, to be manually shortened at will, thereby raising corresponding parts of said edge to form a desired contour for said curtain.

20 14. In combination with a curtain and a pulley system a contour control means for said curtain including a plurality of suitable cleats, positioned near said curtain, and a plurality of vertically disposed flexible members for suspending said curtain therefrom, said members extending each at one end thereof to the lower edge of the curtain and being connected at the other end thereof each to one of said cleats, to be manually shortened at will, thereby raising corresponding parts of said edge to form a desired contour for said curtain.

25 15. In combination with a suspended curtain and a pulley system a contour control means for said curtain, comprising flexible members for raising a plurality of points on the lower edge of said curtain and means for exerting a downwardly pulling force on portions of said curtain, which are positioned intermediately of said points, thereby forming and changing the contour of said curtain at will.

30 16. In combination with a suspended curtain a contour control means for said curtain comprising a means for raising a plurality of points on the lower edge of said curtain and a means for exerting a downwardly pulling force on portions of said curtain, which

are positioned intermediately of said points, thereby forming and changing the contour of said curtain at will.

35 17. In combination with a suspended curtain a contour control means comprising a means for drawing a plurality of points on the lower edge of said curtain in one direction and a means for exerting a force on portions of said curtain positioned intermediately of said points to draw said portions in a direction, which is substantially opposite to said first mentioned direction, thereby forming and changing the contour of said curtain at will.

40 18. In combination with a suspended curtain a contour control means comprising a means for drawing a plurality of points on the said curtain each in one direction and a means for exerting a force on portions of said curtain, which are positioned intermediately of said points to draw said portions each in a direction, which is substantially opposite to the direction in which the points of said curtain which are adjacent to said portions, are being drawn, thereby forming and changing the contour of said curtain at will.

Signed at New York, in the county of New York and State of New York, this 13th day of July, A. D. 1928.

FRANCIS E. WEIDHAAS.
